UNITED STATES PATENT OFFICE.

FREDERIC M. SIMONS, OF PHILADELPHIA, PENNSYLVANIA, ASSIGNOR TO HIMSELF, JOHN F. SIMONS, AND THOMAS MADDOCK, OF SAME PLACE, AND EDWARD S. SIMONS, OF ORANGE, NEW JERSEY.

DESIGN FOR A BUCKLE.

SPECIFICATION forming part of Design No. 28,090, dated December 28, 1897.

Application filed April 24, 1897. Serial No. 633,812. Term of patent 3½ years.

To all whom it may concern:

Be it known that I, FREDERIC M. SIMONS, of the city and county of Philadelphia, State of Pennsylvania, have invented a new and original Design for Buckles, of which the following is a specification.

My design is applied to buckles such as are intended to be worn as articles of dress and is illustrated in the accompanying drawing, 10 which shows a perspective view of such a buckle embodying my design.

A portion of the design relates to the shape or configuration, which is of quadrilateral form, having the two sides A A slightly curved 15 and tapering to the ends a a, where they unite with the extremities of the end pieces B B, which are similarly tapered at their ends b b. The sides A A and ends B B are thus wider at the middle, as at c, and taper toward each 20 end. The edges of the side and end pieces

are rounded, as shown. A transverse bar extends across from one side A to the other, and the tongue D is supported by this bar.

Another portion of my design relates to the surface ornamentation. This consists of the 25 small rose-and-leaf floral pattern upon the surfaces of the sides A A, with the ends B B plain or unornamented.

Having now described my design, what I claim as new, and desire to secure by Letters 30 Patent, is—

The design for a buckle substantially as described and shown.

In testimony of which invention I hereunto set my hand.

FRED. M. SIMONS.
